COMBINED AXLE AND BOLSTER UNIT FOR A TRAILER VAN OR THE LIKE

Grenville C. Stone, 1801 McMillan, Compton, Calif., and
Anthony P. Freitas, 8476 Chestnut, Southgate, Calif.

Filed Nov. 21, 1960, Ser. No. 62,901

Term of patent 14 years

(Cl. D14—2)

FIG. 2

FIG. 1

FIG. 3FIG. 4FIG. 5

FIGURE 1 is a three-quarter front perspective view of a combined axle and bolster unit for a trailer van or the like showing our new design;

FIGURE 2 is a top plan view thereof;

FIGURE 3 is a bottom view thereof;

FIGURE 4 is a front elevational view thereof; and

FIGURE 5 is a side elevational view thereof.

We claim:

The ornamental design for a combined axle and bolster unit for a trailer van or the like, substantially as shown.
